UNITED STATES PATENT OFFICE.

THOMAS L. TALIAFERRO, OF CHICAGO, ILLINOIS.

JAR-CLOSING MACHINE.

Application filed February 8, 1923. Serial No. 617,794.

The invention relates to new and useful improvements in jar closing machines, and more particularly to a jar closing machine wherein the flange of the cap or sealing band is turned underneath the ledge on the neck of the jar for securing the closure to the jar.

An object of the invention is to provide a machine of the above type wherein spinning rolls are utilized for turning the lower edge of the flange of the cap or band underneath the ledge on the jar, and wherein said spinning rolls are so arranged and actuated that the jars may be fed to the spinning rolls one after another at random.

15 A further object of the invention is to provide a machine of the above type wherein the jar passes between the spinning rolls after the flange has been properly turned underneath the ledge on the neck of the jar.

20 A still further object of the invention is to provide a machine of the above type wherein the spinning rolls are made with upper and lower sections, one of which engages the shoulder of the cap or band for forcing it down on to the neck of the jar, and the other of which engages the lower edge of the cap or band and operates to turn or tuck the same underneath the shoulder on the neck of the jar.

25 30 A still further object of the invention is to provide a machine of the above type wherein the sections referred to are yieldingly pressed toward each other so as to permit the same to yield to prevent the crushing of the jar neck where the glass runs very thin.

35 Another object of the invention is to provide a machine of the above type wherein the spinning rolls are so operated that one of the rolls is given a greater surface speed than the other, so as to feed the jar up to the spinning roll and to carry the same between the spinning rolls.

40 45 These and other objects will in part be obvious and will in part be hereinafter more fully disclosed.

In the drawings which show by way of illustration one embodiment of the invention—

50 Figure 1 is a plan view of a machine embodying my improvements;

Fig. 2 is a side view of the same;

Fig. 3 is a view partly in end elevation and partly in section transversely through the machine;

Fig. 4 is a view similar to Fig. 3, but showing a slightly modified form of feeding means, and

Fig. 5 is a plan view of the feed wheels used in the modified form of the invention. 60

The invention is directed particularly to a machine for turning the flange of a cap or band underneath the ledge on the neck of the jar. This is accomplished by two opposed spinning wheels rotating in the same direction and spaced a sufficient distance so as to engage the flange at substantially diametrically opposite points. These spinning wheels are provided with upper and lower sections, the edges of which are reversely inclined to the plane of rotation of the wheels so as to provide an inwardly tapering groove adapted to receive the cap or band. The upper inclined face bears against the shoulder where the flange rests on the 70 top of the jar neck, while the other inclined face engages the lower edge of the flange and bends or tucks the same underneath the ledge. The upper and lower sections of each spinning roll are mounted so that they may yield relative to each other to prevent the breaking of the glass if it runs uneven. One of the spinning rolls is preferably of larger diameter than the other so that they may be driven at the same speed and at the same 80 time, the larger roll will have a greater surface travel. The jars are fed by any suitable means at random to the spinning rolls. As the jar is brought into the space between the spinning rolls, it will be engaged by the 85 two spinning rolls. The smaller wheel rotates in a direction opposed to the travel of the jar as it is brought to the spinning rolls, while the larger roll rotates in the same direction as the travel of the jar. The result is that the larger roll which controls the 90 position of the jar, draws it in between the two spinning rolls and causes the jar to pass between the rolls when the flange has been properly turned underneath the shoulder on the neck of the jar.

100 Referring more in detail to the drawings which show my preferred embodiment of the invention, the machine consists of a supporting frame 1 mounted on legs 2, 2. The 105 frame 1 is in the form of a table extending from the receiving to the delivery end of the machine. Traveling over the table is an endless carrier 3. This carrier runs over a pulley 4 at the delivery end of the ma- 110

chine and the pulley 5 at the receiving end of the machine. The pulley 4 is positively driven by means of a sprocket chain 6 which is operated by a sprocket wheel 7 on the main shaft 8. The main shaft 8 is driven by a belt wheel 9. Said main shaft is mounted in suitable bearings 10, 10 carried by the frame 1. The shaft 11 of the pulley 5 is mounted in a suitable bracket 12 so that it may be moved endwise by means of adjusting bolts 13 to put the endless carrier 3 under tension. The endless carrier 3 runs at a little distance above the table and I have provided rollers 14 and 15 to prevent said endless carrier from sagging.

Extending upwardly from the table is a standard 16 which carries an overhanging arm 17. Mounted in the overhanging arm 17 is a vertical shaft 18 carrying a spinning roll 19. This shaft 18 is mounted in a bearing 20 and is provided with a bevel gear 21 which meshes with the bevel gear 22 carried by the cross shaft 23 mounted in suitable bearings in this overhanging arm 17. On the outer end of the cross shaft 23 there is a sprocket wheel 24. A sprocket chain 25 runs over the sprocket wheel 24 and also over a sprocket wheel 26 on the main shaft 8. Thus it is that the cross shaft 23 is rotated and this will impart rotation to the spinning roll 19.

Also mounted on the overhanging arm 17 is a bearing 27 which is formed in two parts yieldingly pressed toward each other by means of springs 28, 28 encircling bolts 29 passing through the lateral wings carried by the bearing sections. This forms a bearing, the outer half portion of which is capable of lateral movement under the restraint of the springs 28. Mounted in this yieldingly constructed bearing is a shaft 30 which carries the spinning roll 31. The shaft 30 also carries a bevel gear 32 meshing with a bevel gear 33 on the end of the cross shaft 23.

The spinning roll 19 is formed in two sections. The upper section is provided with a downwardly and inwardly inclined face 34 and the lower one is provided with an upwardly and inwardly inclined face 35. The upper section is rigid on its shaft. The lower section is pressed upwardly toward the upper section by means of a spring 36 which encircles the shaft and which bears at its lower end against nuts 37 threaded on to the end of the shaft. This provides a means whereby the lower section can yieldingly move away from the upper section. The spinning roll 31 is likewise formed in two sections with similarly inclined faces 38 and 39. The lower section is also yieldingly pressed upwardly by means of a spring 40 having a similar arrangement to the arrangement of the spring 36. The jar to be closed is indicated at J. The carrier moves in the direction of the arrow as shown in

Fig. 1. The jars are placed thereon and centered on the carrier as near as possible. Suitable guides 41 and 42 mounted on standards 43 and 44, respectively, are arranged so as to insure that the jar is in the center of the carrier as it approaches the spinning rolls. The spinning rolls are set at the proper distance apart, so that the cap or band will pass into the groove formed between the inclined faces and the upper inclined faces of the spinning rolls will engage the shoulder of the cap or band which rests on the neck of the jar while the lower inclined faces of the spinning rolls will engage the lower edge of the flange, the spinning roll 19 is considerably larger in diameter than the spinning roll 31. The spinning rolls are rotated in the direction of the arrows, and it will be noted that the smaller roll has a movement where it contacts with the cap or band in a direction opposed to the direction of travel of the carrier and the jar moves along therewith. The other spinning roll has a movement at the point of contact with the cap or band in the same direction as the direction of the carrier. The result is that as soon as the spinning rolls engage the jar, it will cause the jar to rotate about its axis, and this brings all parts of the flange or cap into engagement with the spinning rolls so that the flange will be gradually bent or tucked underneath the ledge on the neck of the jar. When the flange has been completely tucked underneath the ledge, then the jar will pass between the spinning rolls and of course, will move between the spinning rolls in the same direction as the movement of the carrier which brought the jar up to the spinning rolls. It only takes a short time to turn the edge of the flange on the cap or band underneath the ledge on the jar, and therefore, the jar will quickly pass between the spinning rolls and not interfere with the next approaching jar, so that the jars may be put promiscuously on the carrier without requiring any special timing thereof and they will be taken care of when they reach the spinning rolls. The jars are fed from the endless carrier on to a rotating disk 45. This disk is mounted on a shaft 46 which is rotated by a suitable connection with the shaft carrying the pulley 4. A guide rail 47 directs the jars to one side and any suitable means can be provided, if desired, for taking the jars from this delivery disk.

In Figures 4 and 5, I have shown a slightly modified form of feed, in that I have provided means for insuring that the jar will be brought to a point where it will be gripped by the rotating spinning rolls. To this end, I have provided a vertical shaft 48 which is mounted in a suitable bearing in the frame and is provided with a bevel gear 49 at its lower end meshing with a bevel

gear 50 on the main shaft 8. This vertical shaft 48 carries two spaced feed wheels 51 and 52. These feed wheels are similarly shaped and are provided with segmental pockets 53. These feed wheels, as above described, are positively rotated. The jars are fed into the segmental pockets, and as the feed wheel turns it will press the jar against the spinning rolls and hold the same in engagement with the spinning rolls until gripped and rotated thereby. The feed wheels will also insure that the next succeeding jar is held back until the jar in front thereof has passed on through the spinning rolls.

It is thought that the operation of my device will be apparent from the above description. The operator places the jars with the caps or bands loosely applied thereto, on the carrier slightly spaced from each other, but without any special care as to the exact spacing. The carrier moves the jars forward until they are brought into engagement with the spinning rolls. The spinning rolls engaging the flange of the cap or band will cause the jar to be rotated and will lift the jar to a certain extent from the carrier so that it can be rotated. The jar is rotated for something more than one revolution before the lower edge of the flange is tucked underneath the ledge on the neck of the jar sufficiently to permit the jar to pass between the spinning rolls. The yielding sections of the spinning rolls will give in order to prevent the breaking of the glass if there is unevenness in the vertical thickness of the shoulder on the neck of the jar. The bearing for the smaller spinning roll will yield so as to prevent the breaking of the glass if there is a slight unevenness or out-of-roundness in the neck of the jar.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. A jar closing machine comprising a horizontally traveling carrier, spaced spinning rolls disposed above said carrier so as to engage the flange of a jar closure presented to said spinning rolls by said carrier at diametrically opposite points, said spinning rolls having inclined faces adapted to turn the lower edge of the flange of the closure underneath the shoulder on the jar neck, and means for rotating said rolls in the same direction.

2. A jar closing machine comprising a horizontally traveling carrier, spaced spinning rolls disposed above said carrier so as to engage the flange of a jar closure presented to said spinning rolls by said carrier at

diametrically opposite points, said spinning rolls having inclined faces adapted to turn the lower edge of the flange of the closure underneath the shoulder on the jar neck, and means for rotating said rolls in the same direction, one of said spinning rolls having a greater surface speed than the other, whereby the jar as it is closed is caused to pass between said spinning rolls and move forward with the carrier.

3. A jar closing machine comprising a horizontally traveling carrier, spaced spinning rolls disposed above said carrier so as to engage the flange of a jar closure presented to said spinning rolls by said carrier at diametrically opposite points, said spinning rolls having inclined faces adapted to turn the lower edge of the flange of the closure underneath the shoulder on the jar neck, and means for rotating said rolls in the same direction, one of said spinning rolls being of greater diameter than the other, and means for positively rotating said rolls.

4. A jar closing machine comprising spaced spinning rolls disposed so as to engage a flange of a jar closure at substantially diametrically opposite points, means for rotating said rolls in the same direction, each of said spinning rolls having upper and lower sections, the outer faces of which are inclined to each other so as to engage the flange of the closure and turn the lower edge thereof underneath the shoulder on the jar neck, and means for yieldingly pressing said sections toward each other so that said sections may yield to accommodate any unevenness in the thickness of the glass.

5. A jar closing machine comprising spaced spinning rolls disposed so as to engage a flange of a jar closure at substantially diametrically opposite points, means for rotating said rolls in the same direction, each of said spinning rolls having upper and lower sections, the outer faces of which are inclined to each other so as to engage the flange of the closure and turn the lower edge thereof underneath the shoulder on the jar neck, means for yieldingly pressing said sections toward each other so that said sections may yield to accommodate any unevenness in the thickness of the glass, one of said rolls being larger in diameter than the other, and a carrier for presenting the jars one after another to the spinning rolls and for receiving and conveying the jars away from the spinning rolls after they have passed between the same.

6. A jar closing machine comprising a supporting frame, a carrier mounted on said frame, a standard, an arm carried by the standard and overhanging said carrier, spaced vertically arranged shafts mounted in the standard, a spinning roll carried by each shaft, means for rotating the shafts, each of

said spinning rolls including an upper and a lower section, and means for yieldingly pressing said lower section toward the upper section, the adjacent faces of the sections being inclined toward each other and inwardly from the surface of the rolls whereby the spinning rolls are adapted to engage the flange of a closure at diametrically opposite points and for bending or rolling the lower edge of the flange underneath the ledge on the jar.

7. A jar closing machine comprising a frame, a carrier mounted on said frame, a standard, an arm supported by the standard and overhanging said carrier, vertical shafts mounted in said overhanging arm, means for rotating the shafts, spinning rolls carried by said shafts and having their edges shaped so as to receive the flange of a closure and force the closure on to the jar and turn the lower edge of the flange underneath the ledge on the neck of the jar, a supporting bearing for one of said shafts being formed in sections, yieldingly pressed together in a direction so that the spinning rolls may have a slight movement away from each other to accommodate any unevenness or out-of-roundness in the glass.

8. A jar closing machine comprising a frame, a carrier mounted on said frame, a standard, an arm supported by the standard and overhanging said carrier, vertical shafts mounted in said overhanging arm, means for rotating the shafts, spinning rolls carried by said shafts and having their edges shaped so as to receive the flange of a closure and force the closure on to the jar and turn the lower edge of the flange underneath the ledge on the neck of the jar, a supporting bearing for one of said shafts being formed in sections, yieldingly pressed together in a direction so that the spinning rolls may have a slight movement away from each other to accommodate any unevenness or out-of-roundness in the glass, said spinning rolls being each formed in sections yieldingly pressed together so as to accommodate any unevenness in the glass shoulder on the neck of the jar.

50 9. A machine for capping glass jars and the like comprising in combination, means for supporting the jars to be capped for movement longitudinally through the machine in upright position and in spaced relation, and forming mechanism operable to cause caps on the jars to interlock therewith including a pair of elements disposed on opposite sides of the path of movement of the jars and between which each of the jars is successively positioned, each of said elements being in the form of a roll mounted to turn on a vertical axis and constructed in two sections adapted to engage at their peripheral edges with the caps on the jars whereby to secure them thereon, said sec-

tions with respect to the cap being yieldably mounted along their axes to exert yielding pressure on the caps in a direction parallel to their axes, means operating upon one of said elements to exert yielding pressure on the caps in a direction radially thereof, and means for rotating one of said elements adapted to impart rotary movements to the jars and their caps in such forming operation.

10. A machine for capping glass jars and the like comprising, in combination, means for supporting the jars to be capped for movement longitudinally through the machine in upright position and in spaced relation, and forming mechanism operable to cause caps on the jars to interlock therewith including a pair of elements disposed on opposite sides of the path of movement of the jars and between which each of the jars is successively positioned, one of said elements being in the form of a roll mounted to turn on a vertical axis and constructed in two sections adapted to engage at their peripheral edges with the caps on the jars whereby to secure them thereon, said sections with respect to the caps being yieldably mounted along their axes to exert yielding pressure on the caps in a direction parallel to their axes, means operating upon one of said elements to exert yielding pressure on the caps in a direction radially thereof, and means for rotating one of said elements adapted to impart rotary movements to the jars and their caps in such forming operation.

11. In a capping machine, a pair of power driven rotary capping devices by which the cap is applied to a jar, each capping device comprising a plurality of axially disposed disks, and spring means for yieldingly pressing the disks together axially.

12. In a capping machine, a pair of power driven rotating capping devices by which the cap is applied to a jar, each capping device comprising a plurality of disks rotating about a common center, means for yieldingly pressing the disks together axially, the periphery of the lower disk being conformable to the contour of the part of the jar with which the cap is to be engaged.

13. In a jar capping machine, a pair of power driven rotary capping devices, each capping device comprising a plurality of axially disposed disks, means for yieldingly pressing the disks together axially, and means for passing the jar to be capped between the pair of rotating capping devices to act upon the same whereby the jar will be rotated by the capping devices as it passes therebetween to cause the cap to conform with the neck of the jar with which the cap is to be engaged.

In testimony whereof, I affix my signature.

THOMAS L. TALIAFERRO.
